UNITED STATES PATENT OFFICE.

JOHN H. BOYLE, OF NEW HAVEN, CONNECTICUT.

CLOCK-WINDING MECHANISM.

1,300,113.

Specification of Letters Patent.

Patented Apr. 8, 1919.

Application filed November 7, 1916. Serial No. 130,001.

To all whom it may concern:

Be it known that I, JOHN H. BOYLE, a citizen of the United States, residing at New Haven, in the county of New Haven and 5 State of Connecticut, have invented certain new and useful Improvements in Clock-Winding Mechanism, of which the following is a specification.

The present invention relates to the class 10 of horology and has particular reference to new and useful improvements in main and alarm spring winders for clocks and the like.

As at present constructed and in general 15 use when it is desired to wind the main and alarm springs of a clock a pair of winding spindles must be provided which necessarily interrupts the face of the clock and mars the figures thereon.

20 It is therefore an object of my invention to provide means for winding the alarm and time or main springs of a clock from a single winding spindle which may be located beneath the face of the clock remote from 25 the mechanism.

Another object of my invention is to provide an arrangement of the class referred to which is simple in construction, strong and durable and effective in operation.

30 A further object of my invention is to provide means for preventing unwinding of one of the springs while the other spring is being wound.

Other objects and advantages to be derived from the use of my improved winding 35 mechanism for clock springs will appear from the following detailed description and the claims, taken with an inspection of the accompanying drawings, in which:

40 Figure 1 is a side elevation of a portion of the mechanism of a clock embodying the improvements of my invention;

Fig. 2 is an enlarged view showing the springs removed;

45 Fig. 3 is a rear fragmental elevational view of the winding mechanism of my invention;

Fig. 4 is an enlarged fragmental sectional view of the main winding spindle, and the 50 gears transmitting power therefrom;

Fig. 5 is an enlarged elevation of the main spring spindle.

Fig. 6 is an enlarged longitudinal section of the alarm spring spindle;

55 Fig. 7 is an enlarged detailed perspective

of the ratchet member for association with the spring spindles; and

Fig. 8 is an enlarged transverse sectional view of the main spring drum, showing a portion of the spring.

60

Referring more particularly to the drawings, wherein similar characters of reference designate like and corresponding parts throughout the various views, 10 and 11 designate the supporting frames, rear and front, respectively, of my improved winding mechanism. Supporting frames for the clock-work mechanism are designated 12 and 13, the frame 13 being carried by the frame 11 by means of bolts 14 or the like.

65

70 My invention essentially resides in the provision of a main winding spindle 15 mounted in suitable bearings formed in the frames 10 and 11, the free end of the spindle 15 being squared as at 16 and projecting 75 from the clock housing (not shown) below the face of the clock to permit application of a key thereto.

A shaft 18 is mounted in suitable bearings carried by the frames 10 and 11 in a plane 80 above the spindle 15, said shaft having a main spring drum 19 thereon rotatable therewith. The main spring 21 is secured to the drum 19 by a ratchet mechanism hereinafter described. A sprocket wheel 22 is 85 carried by the rear free end of the drum 19, said sprocket wheel having a chain 23 trained thereover, said chain also being trained over a sprocket carried on the spindle 15.

90

An alarm spring drum 24 is mounted on the shaft 18 and rotatable independently thereof, said drum having a spring anchor projection 25 thereon to which one end of the alarm spring 26 is to be attached. An 95 annual enlargement 27 is formed on the rear free end of the drum 24 and a plurality of recesses 28 are formed in the rear face of the drum. A pawl carrying member 29 in the form of a disk is receivable on the shaft 18 and rotatable with the drum 19, any suitable means being provided for rigidly connecting said disk to said drum. A plurality of spring pawls 30 are struck from the disk 29 and are adapted to normally engage the 100 recesses 28 in the drum 24.

105 Referring specifically to Figs. 5 and 8 it will be seen that I have provided means for connecting the main spring, at times, to the drum 19, said means including a tubular 110

member 32 rotatable upon the drum 19, said drum being provided with a recess 33 in which a spring operated pawl 34 carried by the tube 32 is adapted to engage. One end 5 of the spring 21 is connected to the tube 32 as indicated at 35. The operation of this portion of the device will appear herein-after.

Power is transmitted from the spring 10 members 21 and 26 by means of gear wheels 37 and 38, the gear 37 being carried by the shaft 18 and the gear 38 by the drum 24.

The movement section of the clock embodying the improvements of my invention 15 is carried between the frame members 12 and 13, and motion is imparted thereto by means of a pair of shafts 39 and 40, the shaft 39 having a pinion 41 on the inner end thereof to engage the gear 37, and the shaft 40 having a pinion 42 on its inner end to engage the gear 38. The gears 43 and 44 carried by the shafts 39 and 40, respectively, transmit motion directly to the movement and alarm sections of the clock. To 25 prevent the springs 21 and 26 from unwinding when either of the same is being wound I provide ratchet wheels 46 and 47 carried by the shafts 39 and 40, respectively. The wheels 46 and 47 are oppositely disposed and 30 are engaged by pawls 48 and 49 carried by the frame 12.

The pawls serve to engage their respective wheels upon a tendency of the same to reverse rotation, that is, the pawls permit the 35 normal rotation of the shafts 39 and 40 to operate the movement and alarm mechanism of the clock but prevent any reverse rotation of said shaft.

In operation, upon rotation of the spindle 40 15 in a given direction motion will be imparted to the shaft 18, and assuming that the motion given to the spindle 15 is clockwise motion the main spring 21 will be wound. This will be apparent from an inspection of Fig. 8, the pawl 34 engaging 45 in the recess 33 to cause the tube 32 to rotate with the drum 19. During this action the drum 24 remains stationary, the pawls 30 not engaging the recesses 28. The pawl 49 prevents the alarm spring 26 from unwind-ing.

After the main spring has been wound the direction of rotation of the shaft 15 is reversed which will reverse the drum 19 and

the disk 29 causing the pawls 30 to engage 55 in the recesses 28 in the drum 24 winding the alarm spring.

Thus it will be seen that in the provision of my spring winding mechanism for clocks a practically unlimited space is provided for 60 the springs thereby permitting the installing of larger springs, and in comparison with the usual arrangement of springs less space is occupied thereby. The device also obviates the necessity of opening the clock face 65 for winding which necessarily admits dust to the movement mechanism and the winding mechanism in the clocks now in use. Another advantage of my invention resides in the fact that to construct the same does not 70 require a material increase in the cost.

From the above description taken in connection with the accompanying drawings, it is thought that a clear and comprehensive understanding of the construction, operation 75 and advantages of my invention may be had, and while I have shown and described the device as embodying a specific structure, I desire that it be understood that such changes may be made in said structure as do 80 not depart from the spirit and scope of the invention as claimed.

Having thus fully described my invention, what I claim as new and desire to secure by Letters Patent, is:—

In a spring winding mechanism, a main shaft, a main spring receiving drum fixedly mounted on the shaft, a sleeve loosely mounted on the drum, a pivoted pawl carried by the sleeve engageable in a recess in said drum for connecting the sleeve to the drum upon rotation of the latter in a certain direction, a disk fixedly mounted on the main shaft adjacent one end of said drum, spring pawls struck outwardly from said disk, an alarm spring receiving drum loosely mounted on the main shaft adjacent said first drum having one end thereof formed with recesses to receive the spring pawls on the disk whereby to permit the transmission of rotary motion thereto, at times, and a winding shaft arranged in spaced relation to said main shaft and connected thereto, as and for the purpose set forth.

In testimony whereof, I affix my signature 105 hereto.

JOHN H. BOYLE.
